(57) **CLAIM**

The ornamental design for a combined ceiling fan housing and blade iron assembly, as shown and described.

DESCRIPTION

FIG. 1 is a perspective view from below of a combined ceiling fan housing and blade iron assembly in accordance with my design;

FIG. 2 is an enlarged perspective view from below of a combined ceiling fan housing and blade iron assembly, in accordance with my design;

FIG. 3 is a reduced bottom plan view of the combined ceiling fan housing and blade iron assembly in accordance with my design;

FIG. 4 is a reduced top plan view of the combined ceiling fan housing and blade iron assembly in accordance with my design;

FIG. 5 is a front elevation view of the combined ceiling fan housing and blade iron assembly in accordance with my design; and,

FIG. 6 is a side elevation view of the combined ceiling fan housing and blade iron assembly in accordance with my design.

FIGS. 5 and 6 are identical except for the positioning of the fan blades.

The broken lines showing environmental structure are for illustrative purposes and form no part of the claimed design.
